(57) **CLAIM**

I claim the design for a towing hook, as shown.

DESCRIPTION

FIG. 1 is a perspective view of a towing hook of my new design;

FIG. 2 is a forward end view thereof;

FIG. 3 is a rearward end view thereof;

FIG. 4 is a right side elevational view thereof;

FIG. 5 is a left side elevational view thereof;

FIG. 6 is a top view thereof; and,

FIG. 7 is a bottom view thereof.

The dashed lines in FIGS. 1-7 indicate irregular lines characteristic of welds is included for the purpose of illustrating environment and are not intended to be part of the claimed design.
